Primary Examiner—Bernard Ansher*Assistant Examiner*—Lucy Lieberman*Attorney, Agent, or Firm*—Julie Blackburn[57] **CLAIM**

The ornamental design for a combined bottle and cap with nested vial, as shown and described.

DESCRIPTION

FIG. 1 is a front perspective view from above of a combined bottle and cap with nested vial showing my new design;

FIG. 2 is a front elevation thereof;

FIG. 3 is a left side elevation thereof;

FIG. 4 is a right side elevation thereof;

FIG. 5 is a rear elevation thereof;

FIG. 6 is a top plan view thereof;

FIG. 7 is a bottom plan view thereof; and,

FIG. 8 is a perspective view of the bottle and cap shown in an exploded condition.

The broken line showing of a bottle neck in FIG. 8 is for illustrative purposes only and does not form part of the claimed design.
